TRIMMING AND STITCHING MACHINE

George M. Eames, Bridgeport, Conn., assignor to
The Singer Manufacturing Company, Elizabeth, N. J., a corporation of New Jersey

Application June 29, 1935, Serial No. 29,016

14 Claims. (Cl. 112—124)

This invention relates to sewing machines and more particularly to a sewing machine provided with a rotary cutter whereby the work may be simultaneously stitched and trimmed.

5 The several features of the present invention will be clearly understood from the following description and accompanying drawings in which:

Figure 1 is a front elevation, partly in section, of a sewing machine having my improved trimming mechanism embodied therein.

Figure 2 is a bottom plan view.

Figure 3 is a sectional view taken substantially along the line 3—3 of Figure 1.

Figure 4 is a top plan view of the trimming mechanism located above the cloth-plate, showing the supporting means for the trimmer and its actuating mechanism.

Figure 5 is a sectional view taken substantially along the line 5—5 of Figure 1.

20 Referring to the drawings, 10 represents the bed of the machine upon which is mounted the standard 11 and overhanging bracket-arm 12 terminating in a hollow-head 13. Journaled in the bracket-arm 12 is a main shaft 14 carrying 25 at one end a hand-wheel 15 and having its opposite end operatively connected, by the link 16, to the reciprocatory needle-bar 17, carrying a needle 18.

30 Journaled in the bed 10 is a rotary actuating shaft 19 which is connected in driving relation with the main shaft 14 by means of the belt-pulleys 20 and belt 21, the ratio between the shafts 14 and 19 being one to one. Fixed to the actuating shaft 19 is a gear 22 which meshes with 35 a gear 23 fixed to the loop-taker shaft 24, the gear ratio being two to one, and to the upper end of the shaft 24 there is secured a loop-taker 25, of the vertical axis type, which is disposed on the left side of the needle as viewed in Figure 1.

40 The feeding mechanism comprises a feed-bar 26 located at one side of the loop-taker and carrying the usual feed-dog 27. One end of the feed-bar is pivotally connected to the rock-shaft 28 which is rocked back-and-forth by a pitman 29 actuated by the adjustable eccentric 30 on the main shaft 14. The means for adjusting the eccentric 30 is old and well known and is shown in the patent to Dial et al. No. 718,988, dated Jan. 27, 1903. A rising and falling movement 45 is imparted to the feed-bar 26 from the actuating shaft by means of an eccentric 31 which is fixed to the shaft 19 and the member 32 which is fixed to the feed-bar and provided with arms 33 which embrace the eccentric 31.

50 My improved trimming and actuating mecha-

nism therefor comprises a bracket 34 fixed to the under side of the bed 10 by the screws 35. Rotatably journaled in the bracket 34 is a short vertical shaft 36 having a gear 37 fixed to its upper end and to its lower end there is fixed a clutch-wheel 38. The clutch-wheel is actuated from the actuating shaft 19 by means of an eccentric 39 which is adjustable by means of the screw 39'. The eccentric 39 is connected to an arm 41 by the pitman 40 having one of its ends connected to the eccentric 39 and its other end pivotally connected for universal movement to the arm 41 by the round headed pivot-screw 42. The arm 41 is rotatably mounted on the short shaft 36 and is held thereon by the collar 43. Formed on the arm 41 are notches 44 which receive the ends of the usual spring-biased clutch-dogs 45. A detent 46 is provided to prevent retrograde movement of the wheel 38. The above described clutch, which imparts to the shaft 36 10 a one way intermittent motion, is old and well known and further description is believed unnecessary.

To the top of the cloth-plate there is secured by the screws 47 and 47' a bracket 48 formed with ears 49 carrying the pintles 50 which pivotally support one end of a frame 51. A bushing 52 is adjustably secured by the screw 53 to the frame 51 and a second bushing 54 is adjustably secured by the screw 55 to the other end of the frame. Journaled in the bushings 52 and 54 is a shaft 56 having secured to one of its ends by the set-screw 57 a gear 58 which meshes with the gear 37 carried by the shaft 36. Carried by the other end of the shaft 56 is a cutting wheel 59 which is fixed to the shaft for rotation therewith by the headed bolt 59 which extends through a longitudinal aperture in the shaft 56 and is held therein by a nut 60.

The cutting wheel 59 cooperates with a platen 40 roller the outer periphery of which extends through an opening in the throat-plate 74. The platen roller comprises an outer race-member 61, an inner race-member 62 with a series of anti-frictional elements 63 interposed therebetween. 45 The inner race-member 62 is fixed to the end of the stud 64 which is clamped in the split hub 65 of the supporting saddle 66 by the screw 67. The saddle 66 is adjustably secured to the bed of the machine by means of a cap-screw 68 which extends through the elongated aperture 69 in one leg of the saddle and is threaded into the boss 70 formed on the bed of the machine, the other leg of the saddle being formed with a split hub 55

11 which is clamped to the bushing 12 by the screw 73.

The frame 51 is urged upwardly about its pivots by a spring 75 which has one of its ends 5 clamped to the bracket 48 by the screw 47 and its free end bent so as to underlie a portion of the frame 51. In order to hold the cutting wheel 58 against the outer periphery of the race-member 61 and to provide means for adjusting the 10 pressure therebetween, the frame 51 is formed with a reduced cylindrical portion 76 which carries a collar 77 formed with a slot 78 and a portion 80 which acts as a guard and stripper for the cutting wheel 58. To hold the collar 77 on 15 the reduced portion 76, a screw 79 is provided which extends through the slot 78 and is threaded into the cylindrical portion 76. This construction permits the collar 77 to be turned about the cylindrical portion 76. Formed on the collar 77 20 is a boss 81 which is tapped to receive the threaded end of the screw 82 and the other end of the screw enters a notch in the head of the machine. From the above it will be obvious that by adjusting the screw 82 the pressure between the cutting wheel and the platen roller may be 25 regulated and, when desired, the screw 82 may be loosened and the collar 77 together with the screw shifted backwardly to permit the spring 75 to raise the frame 51 and cutting wheel 58 above 30 the work in order that the machine may be used for the purpose of stitching only.

When the machine is operated the needle 18 and hook 25 operate in timed relation to form 35 stitches and the feed-dog 27 advances the work in a right line. It is to be understood that the shafts 14 and 19 rotate at the same speed, the hook 25 rotates at twice the speed of these shafts and the feed-dog operates once for each rotation of the shafts 14 and 19.

40 Rotation of the shaft 19 causes the adjustable eccentric 39 to actuate, through the pitman 40, the arm 41 and clutch-dogs 45 which impart a step by step intermittent motion to the clutch-wheel 38 and shaft 36 and this motion is transmitted to the cutting wheel 58 by the shaft 56 and the gears 37 and 57. The pressure between 45 the cutting wheel and platen roller severs the material and the movement of the cutting wheel acts as a feed for the material and, therefore, it is necessary to synchronize the movement of the cutting wheel with the feed-dog. This is accomplished by adjusting the screw 39' of the eccentric 39. Also when the throw of the feed-dog is varied by adjusting the eccentric 30 the 55 screw 39' may be adjusted to vary the amount of movement given to the cutting wheel and thus synchronize the two work-advancing elements.

By placing the rotary hook at one side of the line of seam formation and the platen roller on 60 the other side, the platen roller may be placed close to the needle and a conventional ball-bearing may be used for the platen roller. Further, interference between the hook and platen roller is avoided. It will also be observed that there are 65 no oscillating or vibrating parts above the bed which might injure the operator or interfere in any way with the use of the machine for plain stitching operations.

70 From the foregoing description considered in connection with the accompanying drawings, the construction, manner of operation and several advantages of my improved stitching and trimming machine will be clearly and fully understood. It is apparent that such a device has a 75 wide variety of uses, and it will be understood

that the form, construction and arrangement of the several elements employed may be varied. Therefore, the privilege is reserved of resorting to all such legitimate changes therein as may be fairly embodied within the spirit and scope 5 of the appended claims.

Having thus set forth the nature of the invention, what I claim herein is:—

1. A sewing machine having in combination a 10 bed, an overhanging bracket-arm terminating in a hollow head carried by said bed, a reciprocatory needle, needle actuating means, an actuating shaft journaled in said bed, a vertically disposed hook-shaft journaled in said bed, gearing between 15 said shafts, a hook carried by said hook-shaft and located at one side of the needle path, a rotary trimmer located at the other side of said needle-path, and means for actuating said trimmer.

2. A sewing machine having a bed, a feed-dog 20 for advancing the work and located below said bed, a rotary hook disposed at one side of said feed-dog, a platen roller disposed at the other side of said feed-dog, and a circular cutter located above said bed and cooperating with said platen roller to sever material. 25

3. A sewing machine having sewing instrumentalities including a rotary hook, a bed, a rotary actuating shaft journaled in said bed, means operatively connecting said rotary hook with said rotary shaft to cause the rotary hook to rotate 30 at twice the speed of the shaft, an adjustable eccentric carried by said shaft, a rotary cutting wheel for severing material and means operatively connecting said eccentric with said cutting wheel. 35

4. A sewing machine having sewing instrumentalities including a rotary hook, a rotary actuating shaft, means operatively connecting said rotary hook with said rotary shaft to cause the rotary hook to rotate at twice the speed of the 40 shaft, an adjustable eccentric carried by said shaft, a rotary cutting wheel for severing material and means operatively connecting said eccentric with said cutting wheel. 45

5. A sewing machine having a bed, a rotary shaft journaled in said bed, a rotary loop-taker actuated by said shaft, a vertical shaft extending 50 upwardly through said bed, means actuated by said rotary shaft for imparting a step by step rotary movement to said vertical shaft, a rotary cutting wheel, and means operatively connecting said rotary cutting wheel to said vertical shaft. 55

6. A sewing machine having in combination, a bed, sewing instrumentalities including a reciprocatory needle located above said bed, feeding mechanism for advancing the work, a loop-taker located below said bed and at one side of the line 60 of feed, a rotary cutter located at the other side of the line of feed, and means for actuating said rotary cutter.

7. A sewing machine having in combination, a bed, sewing instrumentalities including a reciprocatory needle located above said bed, feeding mechanism for advancing the work, a loop-taker located below said bed and at one side of the line of feed, a platen roller located below 70 said bed and on the other side of the line of feed, a circular cutter cooperating with said platen roller, and means for imparting a step by step rotary movement to said cutter. 75

8. A sewing machine having in combination, a bed, an overhanging bracket-arm carried thereby,

- a reciprocating needle, a needle-actuating shaft journaled in said bracket-arm, a rotary shaft located in said bed, means connecting said needle-actuating shaft and rotary shaft for rotation at 5 the same speed, a loop-taker shaft, a loop-taker carried thereby, means for actuating the loop-taker shaft at twice the speed of the rotary shaft, a cutting wheel located above said bed adjacent the needle and means for actuating said cutting 10 wheel from said rotary shaft.
9. A sewing machine having in combination, a bed, an overhanging bracket-arm carried thereby, a reciprocating needle, a needle-actuating shaft journaled in said bracket-arm, a rotary shaft 15 located in said bed, means connecting said needle-actuating shaft and rotary shaft for rotation at the same speed, a loop-taker shaft, a loop-taker carried thereby, means for actuating the loop-taker shaft at twice the speed of the rotary shaft, 20 a cutting wheel located above said bed adjacent the needle, an adjustable eccentric carried by said rotary shaft, a one-way clutch actuated by said eccentric, and means operatively connecting said clutch with said cutting wheel.
- 25 10. A sewing machine having, in combination, a bed, a standard and overhanging bracket-arm carried thereby, a reciprocating needle-bar carrying a needle, a needle-bar shaft, a rotary shaft journaled in said bed, means interconnecting said 30 shafts whereby they are caused to rotate at the same speed, a hook-shaft carrying a rotary hook, gearing interconnecting said hook and rotary shafts whereby the hook-shaft is caused to rotate at twice the speed of the rotary shaft, an adjustable eccentric carried by said rotary shaft, a one-way clutch actuated by said eccentric, a vertical shaft extending through said bed and actuated by said clutch, a shaft carrying a circular trimmer located above said bed, gearing 35 40 connecting said last mentioned shaft with said vertical shaft and a platen roller located adjacent the needle and cooperating with said circular trimmer to sever material.
11. A sewing machine having, in combination, 45 a bed, a standard and overhanging bracket-arm carried thereby, a reciprocating needle-bar carrying a needle, a needle-bar shaft, a rotary shaft journaled in said bed, means interconnecting said shafts whereby they are caused to rotate at the same speed, a hook-shaft carrying a rotary hook, gearing interconnecting said hook-shaft and rotary shaft whereby the hook-shaft is caused to rotate at twice the speed of the rotary shaft, an
- adjustable eccentric carried by said rotary shaft, a one-way clutch actuated by said eccentric, a vertical shaft extending through said bed and actuated by said clutch, a shaft carrying a circular trimmer located above said bed, gearing 5 10 connecting said last mentioned shaft with said vertical shaft and a platen roller cooperating with said circular trimmer and located below said bed and adjacent said needle, and means for regulating the pressure between said circular trimmer and said platen roller.
12. A sewing machine having in combination a bed, sewing instrumentalities including a reciprocating needle, feeding mechanism for advancing the work, a rotary hook cooperating with 15 said needle and operating about a vertical axis located at one side of the line of feed, a shaft journaled in said bed and operating at one-half the speed of the rotary hook, a rotary cutter located above the bed and at the opposite side of 20 the line of feed from said hook, a platen roller cooperating with said cutter, and mechanism actuated by said shaft for imparting a step by step movement to said rotary cutter.
13. A sewing machine having in combination 25 a bed, sewing instrumentalities including a reciprocating needle, feeding mechanism for advancing the work, a rotary hook cooperating with said needle and operating about a vertical axis located at one side of the line of feed, a shaft 30 journaled in said bed and operating at one-half the speed of the rotary hook, a rotary cutter located above the bed and on the opposite side of the line of feed from said hook, a platen roller located below said bed and cooperating with said 35 rotary cutter, said platen roller being a conventional ball-bearing, mechanism including a one-way clutch for actuating said cutter and an adjustable eccentric carried by said shaft for actuating said clutch.
14. A sewing machine having in combination, 40 a work-support, a bracket-arm terminating in a hollow-head and overhanging said work-support, a needle-bar shaft journaled in said bracket-arm, a reciprocating needle-bar journaled in said hollow-head and carrying a needle, a frame mounted upon said work-support, a shaft journaled in said frame, cooperating rotary cutter elements one of which is carried by said last mentioned shaft, and means interposed between 45 50 said bracket-arm and frame for adjusting said rotary cutter elements relative to each other.

GEORGE M. EAMES.
